UNITED STATES PATENT OFFICE

WILLIAM WESLEY DWIGANS AND JOE M. ADAMS, OF ARKADELPHIA,
ARKANSAS.

RAFTER-SCALE.

No. 814,948.

Specification of Letters Patent. Patented March 13, 1906.

Application filed November 15, 1905. Serial No. 287,452.

To all whom it may concern.

Be it known that we, WILLIAM WESLEY DWIGANS and JOE M. ADAMS, citizens of the United States, and residents of Arkadelphia, in the county of Clark and State of Arkansas, have invented a new and Improved Rafter-Scale, of which the following is a full, clear, and exact description.

This invention relates to mechanics' tools. The object of the invention is to provide a convenient plumb-scale for finding the lengths of rafters of various pitches and for different widths of buildings.

The invention consists in the construction and combination of parts to be more fully described hereinafter and definitely set forth in the claims.

Reference is to be had to the accompanying drawings, forming a part of this specification, in which similar characters of reference indicate corresponding parts in all the figures.

Figure 1 is a front elevation of the scale, showing a portion of a level to which the invention is conveniently attached. Fig. 2 is a vertical central section through the device. Fig. 3 is a front elevation of the device upon a reduced scale, illustrating how the device is used in practice and showing the pointer thereof operating with one of its scales; and Fig. 4 is a view similar to Fig. 3, but representing the device in an opposite position and showing the pointer operating with an opposite scale.

Referring more particularly to the parts, 1 represents the body of a spirit-level such as is used by carpenters. At a convenient point on this body we attach a dial-case 2, the same being preferably mounted in a recess 3, formed in the face of the body 1, as will be readily understood. This dial-case is formed with a central hub 4, which is received in an opening 5, formed in the body, as indicated, and this opening is counterbored at the rear, 45 so as to form a recess 6. The hub 4 of the case 2 is provided on its inner face with a bore 7. This bore 7 receives a hub 8, which is formed on the inner face of a dial 9, and the lower edge 10 of this dial is graduated, as shown. The rear side of the lower portion of the dial is provided with a counterweight 11, which normally holds the dial in the position shown in Fig. 1. In this position the zero-

mark of the dial is disposed in a vertical line below the center of the dial, and the degrees 55 are laid off successively from this point in both directions. We prefer to mark the forty-five-degree lines on both sides by numerals, and on one side we indicate the thirty-degree mark, as shown. As viewed in Fig. 1, in the 60 vertical central line of the dial, above the center thereof, we provide a plurality of threaded openings 12, which are adapted to receive a removable threaded pin 13. This pin affords means for attaching a pointer 14, which 65 is hung normally in a vertical position from a pivoting-pin 15, attached on the casing 2. It engages the pin 13 by means of a longitudinal slot 16, through which the pin passes, as will be readily understood. On the upper 70 portion of the face of the dial we provide a plurality of curves 17, which constitute scales. There are four of these scales disposed on each side of the central line, so that two sets are formed, and these two sets 75 are similar in form, but opposites. The scales to the left are represented individually by the characters A, B, C, and D, and those at the right by the characters a, b, c, and d. If the pin 13 is attached in the uppermost of the 80 openings 12, as indicated in Fig. 1, and the dial is then rotated, the free extremity of the pointer 14 will move along either the scale A or a. If the pin 13 is placed in the second opening, the extremity of the pointer will 85 move along either the scale B or b, &c. The scales A, B, C, and D are devoted to the measurement of hip-rafters, while the opposite scales are devoted to the measurement of straight rafters. These different scales are 90 graduated, so that when the dial is set at a certain angle with relation to a fixed point, such as the point 17^a on the casing, the extremity of the pointer will indicate on the corresponding scale the length of the rafter 95 required. The four different scales on each side correspond to different widths for the building—that is, the outside scales A and a correspond to a building width of twenty feet. In other words, the uppermost pin position, 100 as shown in Fig. 1, corresponds to a building width of twenty feet, the next position corresponds to a building width of eighteen feet, the next to a building width of sixteen feet, and the lowest position of the pin corresponds 105 to a building width of fourteen feet. In this

way we are enabled to measure or determine the lengths of rafters, whether hip-rafters or straight rafters, for any given pitch of roof and for any of the widths of building referred to. 5 Thus in Fig. 3 the pointer is indicating the proper length of a hip-rafter for a building of twenty-feet width with a pitch of forty-five degrees. In Fig. 4 the instrument is indicating the length of a straight rafter for a building of the same width, but having a pitch of thirty degrees.

For the purpose of enabling the dial to swing freely we prefer to mount the hub 8 thereof on ball-bearings 18, the parts being 15 retained in position by means of a central pin 19, receiving a nut 20, disposed in the recess 6 at the back and screwing up against the rear face of the hub 4.

The graduations on the dial enable the device to be used to measure the degree of inclination of a timber already in position. In using the device for this purpose the body or bar 1 will be laid upon the upper or lower edge of the timber, as will be readily understood. 25 In this way the device may be used as an ordinary level to show whether a beam or floor is horizontal.

Having thus described our invention, we claim as new and desire to secure by Letters 30 Patent—

1. An instrument of the class described, comprising in combination, a dial - case, a graduated dial rotatably mounted therein, a pointer pivoted on said case, a pin adapted to 35 be fixed in said dial and engaging said pointer

to guide the same upon said dial, said dial having scales coöperating with said pointer.

2. In an instrument of the class described, in combination, a dial-case, a graduated dial 40 rotatably mounted therein, a pointer pivotally attached to said case and having a longitudinally-disposed slot therein, a pin passing through said slot, means for attaching said pin to said dial in a plurality of positions, said dial having scales formed on the face thereof 45 coöperating with said pointer and corresponding to the different positions of said pin, said scales representing rafter lengths.

3. In an instrument of the class described, in combination, a dial-case, a counterweighted dial rotatably mounted thereon and having graduations on the edge thereof, a pointer 50 depending from said case across the face of said dial and having a longitudinal slot therein, a pin passing through said slot, and means for attaching said pin to said dial in a plurality of positions, the said dial having a plurality of curved graduated scales thereon giving the lengths of rafters corresponding to different pitches thereof, said scales coöperating with said pointer. 55

In testimony whereof we have signed our names to this specification in the presence of two subscribing witnesses.

WILLIAM WESLEY DWIGANS.
JOE M. ADAMS.
